CLAIM

The ornamental design for a point of sale terminal, as shown and described.

DESCRIPTION

FIG. 1 is a top, front, and left side perspective view of a point of sale terminal showing our new design;

FIG. 2 is a right side elevational view thereof on a reduced scale;

FIG. 3 is a rear elevational view thereof on a reduced scale;

FIG. 4 is a bottom plan view thereof on a reduced scale. The keys are shown in broken lines in FIGS. 1 and 2 for illustrative purposes only and thus forms no part of the claimed design.

FIG. 1

FIG. 2***FIG. 3******FIG. 4***
